CLAIM

The ornamental design for a Christmas tree collar as shown and described.

DESCRIPTION

FIG. 1 is a top perspective view of a Christmas tree collar showing my new design;

FIG. 2 is a bottom perspective view thereof;

FIG. 3 is a front elevational view, the rear elevational view, the left side view and the right side view are identical;

FIG. 4 is a top plan view thereof;

FIG. 5 is a bottom plan view thereof;

FIG. 6 is an enlarged view thereof, taken from encircled portion 6 in FIG. 1;

FIG. 7 is an enlarged view thereof, taken from encircled portion 7 in FIG. 1;

FIG. 8 is an enlarged view thereof, taken from encircled portion 8 in FIG. 1;

FIG. 9 is an enlarged view thereof, taken from encircled portion 9 in FIG. 2; and,

FIG. 10 is an enlarged view thereof, taken from encircled portion 10 in FIG. 5.

The broken lines in the drawings represent portions of the Christmas tree collar and form no part of the claimed design.
